MOP

Thomas Hill, Detroit, Mich., assignor to D. H. Gilerist, Detroit, Mich.

Application December 26, 1930
Serial No. 504,792

2 Claims. (Cl. 15—120)

The present invention relates to that type of device known as a self wringing mop or as a combined mop and wringer and is an improvement over the mop shown in my Patent No. 1,678,497. 5 The chief object of the improvement is to enable the mop to employ any rags of the proper length as mopping material, without any special preparation, and to facilitate their being fastened into place.

10 My invention possesses numerous other advantages that will be characterized during the course of the following detailed description, illustrated throughout the accompanying drawings, and more particularly pointed out in the appended 15 claims.

With reference to the drawings:

Figure 1 is a plan view of the complete invention, and broken as indicated.

Figure 2 is a side elevation of the important 20 part of the invention showing the jaws thereof in an opened position.

Figure 3 is a section taken substantially upon line 3—3 of Figure 1.

Figure 4 is a section substantially upon line 25 4—4 of Figure 1.

Figure 5 is an inner plan view of one of the jaw members of the device, and Figure 6 is a similar view of the opposing jaw member.

Figure 7 is an inner plan view of the jaw member operating lever.

Figure 8 is a section substantially upon line 30 8—8 of Figure 2.

Figure 9 is an underneath plan assembly of the device and broken as shown.

Figure 10 is a clear illustration of the device 35 in the act of wringing the mop cloths thereof, with handle broken as indicated.

Figure 11 shows how the jaw end of the device will appear when it is ready for use.

40 Figure 12 clearly illustrates the device in the act of drying the cloths thereof.

Figure 13 is a section substantially upon line 13—13 of Figure 9.

The invention comprises a handle portion 1, 45 which may be formed of a steel tubing or of wood, preferably the latter in order to eliminate excessive weight. The front end of the said handle has a portion thereof reduced in diameter to receive the telescopically engaged sleeve member 2 which is of metal, and with reference to Figure 1 it is observed that one end of this sleeve is forked at 3, and the purpose of the portion 3 is to support the mechanism of the device, further explanation presently follows.

55 Members 4 and 5 are provided as seen in Fig-

ures 5 and 6, and it is noted that these members are respectively formed of a single sheet of metal. Member 4 having teeth 6 and 7 formed thereupon, while member 5 has similar teeth 8 and 9, and the particular construction of the said teeth is to effect a firm grip upon the ends of the cloths A, as seen in Figures 10, 11 and 12.

With reference to Figures 5 and 9, member 4 has extended portion 10 adapted to be positioned within fork 3 of sleeve 2, and member 5 has extended portion 11 adapted to be positioned within portion 10 of member 4. Lever 12 is provided and formed as shown, the said lever is pivotally secured to member 4 by shouldered rivets 13, and likewise to member 5 by rivets 14. The three 60 pivots 13, 14 and 15 are joined by three elements 65 comprising the jaw carrying members 10 and 11 and the operating lever 12. This however may appear to form a rigid triangle, but actually the deflections 15 in member 11 permit the same to 70 elongate under tension and thus permit the pivot 13 to snap past the plane in which lie the pivots 14 and 16. This snap action together with friction retains the jaws closed upon the mop. Raised 75 portions 15 of part 11 of member 5 provide a 80 clearance for passage of the heads of rivets 14.

In Figure 9 the entire mechanism of the device is mounted upon fork 3 of sleeve 2 by means of transversely extending stud 16, spacing sleeve 17 and washers 18 where shown. This arrangement permits the mechanism of the device to pivot relative to the handle thereof, and in the position of any angle preferred; an example of this fact is revealed in Figures 2 and 10.

Rod 19 is provided, one end of which is formed 85 into a suitable crank as at 20, and having knob 21 secured thereto, the said rod adapted to freely pass through an aperture in part 10A and upturned part 10B of member 4. The opposite end of rod 19 being formed into a T head as at 22 in Figure 1, and the portion 22 brazed or welded to elongated loop bars 23 in order that the same may be freely rotated by the rod 19 when desired for the purpose of wringing or drying cloths A. When 90 this connection is complete bars 23 will be at 100 right angles to rod 19, as clearly seen in Figure 10.

With reference to Figures 1 and 11, which show the position of the device for mopping purposes, elongated recess 24 is provided within handle 1, and is adapted to receive rod 19, and in Figures 1 and 4 it is clearly observed that spring clasp 25 is employed to engage the said rod where shown, and the said spring secured to handle 1 by 105 screw 26.

Throughout the drawings the device is illustrated with a double cloth arrangement, whereas a single cloth may be used if preferred without affecting any change of the device or the operation thereof.

The complete details of construction of the device having just been explained, the operation thereof immediately follows:

The cloths A are drawn through bars 23 and 10 their ends placed between teeth 6, 7, 8 and 9 of members 4 and 5 respectively, the jaws being open as in Figure 2, lever 12 is then pressed downwardly to the position shown in Figure 3, the 15 ends of the said cloths are now fixed by a firm grip within the said jaws and the device is ready to be used for mopping purposes, as in Figure 11.

A novel feature of the device is the simple operation thereof for drying cloths A, and this is 20 accomplished by merely elevating rod 19 from recess 24 in handle 1 and sliding the same to the position as indicated in Figure 12, and again placing the rod into the said recess for retaining the same in the cloth-drying position of the device, and the latter may be changed to the position as in Figure 11 in the same simple manner.

Cloths A are very quickly and effectively wrung by sliding rod 19 to the position as in Figure 12 and permitting the said rod to pivot 30 approximately 90 degrees in relation to handle 1, and by rotating the said rod by crank 20 thereof, until cloths A will have assumed the rigidly twisted position clearly revealed in Figure 10. This feature alone is indeed a decided 35 advantage in view of eliminating the necessity of placing the hands into the water, and also the twisting of the cloths by hand, as in many types of mops used.

By substituting cloths A with cloths for polishing purposes the device becomes an effective

floor polisher and would be serviceable for other similar operations.

One of the advantages of my invention, and one of no less importance than those hereinbefore stated is that due to the simple manner of construction employed it may be manufactured at an exceedingly low cost, and placed upon the market at a price well in keeping with its quality, and within reach of all classes of trade, consequently its value from a commercial viewpoint can not of course be overly estimated.

Having thus described my invention, what I claim as new is:

1. A combined mop, wringer and dryer comprising a handle, a jaw transverse to and pivoted at one end of the said handle, a second jaw pivoted to and opposed to the first-named jaw, means to open and close the said jaws, a rod slidably and rotatably mounted on the first-named jaw, said jaw being perpendicular to and passing between the said jaws through a gap in the mop clamping portion of one of the said jaws when the same are closed, and lying along the said handle when the device is in use for mopping purposes, a pair of transverse elongated loops at the end of the said rod projecting from the jaws, one of the said loops being at each side of the axis of the rod, and means to rotate the said rod.

2. A combined mop, wringer and dryer as set forth in claim 1, in which the loops at the end of the rod lie in oblique planes sloping toward the opposite end of the rod so that when the loop carrying end of the rod is drawn up to the jaws of the device the outer portion of each of the said loops will lie one on each side of the jaws.

THOMAS HILL.
